UNITED STATES PATENT OFFICE.

EDWARD F. SEERY, OF PROVIDENCE, RHODE ISLAND.

DESIGN FOR AN ORNAMENTAL CHAIN-LINK.

SPECIFICATION forming part of Design No. 11,790, dated May 25, 1880.

Application filed February 28, 1880. Term of patent 7 years.

To all whom it may concern:

Be it known that I, EDWARD F. SEERY, a citizen of the United States, residing at Providence, in the county of Providence and State 5 of Rhode Island, have invented and produced a new and original Design for Ornamental Chain-Links, of which the following is a specification, reference being had to the accompanying drawings, forming part thereof.

10 Figure 1 is a side view of a chain-link in which a loop made of a metal strip has a spiral wire inclosed between the loop, two connecting-rings secured one at each end, and two rings, one near each end, surrounding the loop.

15 Fig. 2 is a side view of the loop provided with two rings, one near each end, and two connecting-rings. The loop is shown ornamented on the sides. Fig. 3 represents a loop like the loop shown in Fig. 2, twisted one-quarter turn,

20 so that the two connecting-rings are turned in opposite directions. Fig. 4 is a view of a chain-link like the one shown in Fig. 1, differing only in the proportions, the link being shorter and the rings, near the ends of the loops, wider

25 than those shown in Fig. 1.

In the drawings, *a* represents a loop of metal the sides of which are ornamented, as shown in Figs. 2 and 3. *b* is a twisted wire. It may be a beaded wire or other round filling-piece,

30 and may be colored differently from the rest of the link to produce a good effect.

c c are two rings or circular sleeves placed over the ends of loop *a*, so as to let the semi-circular end of the loop project beyond the

35 same, and so as to hold the loop *a* against the

central core, *b*, and which core extends into the rings *c c*.

d d are small connecting-rings, by means of which the links are connected to form a chain.

Various effects may be produced by making 40 the rings *c c* wider or narrower, as also by coloring the different parts in different shades, as also in making them of different metals. A good effect is produced by twisting the links, as is shown in Fig. 3.

Heretofore ornamental chain-links have been made of loops of wire inclosing a twisted or beaded center, and square sleeves were placed near the ends of the loops. In such chain-links the central core of twisted or beaded wire 50 formed too prominent a feature of the design.

By using a strip of metal ornamented on the sides, as shown in Figs. 2 and 3, and placing rings or circular sleeves near each end of the loop, a fine and ornamental effect is produced. 55

Having thus described my invention, I claim as new and desire to secure by Letters Patent—

The design for an ornamental chain, consisting in the ornamental band forming the loop 60 *a*, the central core, *b*, the rings *c c*, surrounding the loop near its ends, and the rings *d d*, substantially as described, and shown in the accompanying drawings.

In witness whereof I have hereunto affixed 65 my name.

EDWARD F. SEERY.
